UNITED STATES PATENT OFFICE

FRANK G. GRAMM, OF CORAOPOLIS, PENNSYLVANIA

BOAT CONSTRUCTION

Application filed July 8, 1929. Serial No. 376,782.

This invention relates to a boat, the general object of the invention being to construct the hull of the boat from flanged plates, the flanges of which are suitably connected together, with spaced T irons connected with the plates for strengthening the same and other T irons extending at right angles to the first mentioned irons and having notches therein for receiving portions 10 of said other irons whereby a hull is formed of considerable strength and one in which the sections may be formed in a shop and then the sections assembled where the boat is to be launched, and the invention enables 15 a boat to be constructed in the minimum amount of time and with the minimum amount of labor.

This invention also consists in certain other features of construction and in the 20 combination and arrangement of the several parts, to be hereinafter fully described, illustrated in the accompanying drawings and specifically pointed out in the appended claim.

25 In describing the invention in detail, reference will be had to the accompanying drawings wherein like characters denote like or corresponding parts throughout the several views, and in which:—

30 Figure 1 is a transverse sectional view through a boat constructed in accordance with this invention, the section being taken on line 1—1 of Figure 2.

Figure 2 is a section on line 2—2 of Figure 1.

Figure 3 is a view of one of the plates used in the construction of the boat.

Figure 4 is a view of the blank from which the plate is formed.

40 Figure 5 is a perspective view of part of the boat.

Figure 6 is a fragmentary longitudinal sectional view showing the plates riveted together.

45 As shown in these views, the central section A of the boat is constructed of plates 1 each having two of the opposing edges bent at right angles to form the flanges 2, these flanges either being welded together, as 50 shown in Figures 1 and 2, or riveted together

by the rivets 3, as shown in Figure 6. When the flanges are riveted together, packing strips 4 are placed between the flanges, as shown in Figure 6. One end of each plate is formed with a slightly curved tongue 2' 55 to receive the opposite end of the next plate, as shown in Figure 2, the joggled seams extending transversely of the boat. These seams are formed by welding or otherwise.

Some of the plates are curved, as at 5, to 60 form the side corners of the boat and each plate is strengthened by a plurality of spaced T irons C which extend longitudinally of the plates and the central section and the parts are still further strengthened by the T irons 7 which extend at right angles to the members 6 and are notched, as at 8, to receive portions of the members 6. The T irons 7 are also notched to receive the flanges of 65 the plates. The flanges 2 are strengthened by the braces 9 which extend from the free edges of the flanges to the plates. Some of the T irons 6 are arranged at the corners 5 and those portions of these T irons which are connected with the plates are curved to 70 conform with the curve of the plates.

The T irons 6 may be welded to the plates and they should be bowed a predetermined amount before welding to counteract contraction, due to the welding operation. They 75 may be spot welded in place and later a tractor type arc welder can be used to weld the T irons to the plates. Two of the T's 80 can be welded at one time so that one operator could operate the two machines simultaneously. The struts or braces 9 can also be welded in position or the various parts can be riveted together instead of being welded.

The ends B of the boat may be formed 85 the same as the central part thereof, or each end may be formed as shown in Figure 2, which shows the T irons 6' extending transversely of the boat and the T irons 7' extending longitudinally thereof. This view also shows the flanges 2'' of the plates extending 90 transversely. Of course, other shapes of beams may be used in place of the T irons and brace members 10 may be placed wherever desired. Bulkheads 11 are also placed 95 wherever desired, these heads being formed 100

of plates notched to receive the beams and welded or otherwise fastened in place.

A boat, constructed according to this invention, will require no layout, punches, beveled shearing and no riveting when the parts are welded together. The invention provides flexibility of design and maximum strength, with minimum dead weight and also provides the maximum of flat welding which is adaptable to various types of automatic welding. The parts are preferably assembled in sections and the parts welded or riveted together and then the sections are swung into place and connected together.

Barges of any description, tow boats, pontoons, dump scows and similar boats may be constructed in accordance with this invention.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A boat having its hull constructed of plates having flanges on some of their edges, the flanges of each plate being connected with the flanges of adjacent plates, means for fastening the other edges of each plate to other plates, T beams having their base parts connected with the inner faces of the plates and other T beams extending at right angles to the first beams and having notches therein receiving portions of the other beams.

In testimony whereof I affix my signature.

FRANK G. GRAMM.
